ATTORNEY

UNITED STATES PATENT OFFICE.

DEZSO BALAZS, OF SAN FRANCISCO, CALIFORNIA.

CLASP FOR HAND BAGS AND LIKE RECEPTACLES.

Application filed May 24, 1926. Serial No. 111,125.

The present invention relates to improvements in clasp means generally, and more particularly to those for securing in closed relation the hinged frames of hand-bags, 5 mesh-bags, and like receptacles.

The usual practice has been to employ clamping means of various forms to hold the frames of such receptacles in closed relation, but the form most usually employed 10 consists of a male spring catch-member mounted upon one of the hinged frames and adapted to engage a female member mounted upon the other frame. Such a construction is very unsatisfactory, becoming of un- 15 certain operation and little value after worn, on account of a weakened spring tension.

It is the primary object of the present construction to provide a clasp that will be positive in its action, cheap and ornamental, 20 and that will retain its efficiency unimpaired and indefinitely under the most exacting condition of service.

Another object is the provision of a clasp of the character designated that may be 25 readily applied to any design of hand-bag having metallic hinged frames.

A further object of the invention is the provision of a clasp most suitable for hand-bags having their hinged frames covered by 30 an entire body constituted of leather, the clasp-engaged section being so protected that the clasp does not come in wearing contact with a leather portion.

Other objects and advantages will appear 35 with reference to the specification and accompanying drawings, and be more fully set forth in the claims hereto appended.

In the drawings, forming a part of this 40 specification, and in which similar characters of reference refer to like parts, throughout,—

Figure 1 is a side elevation of a lady's 45 hand-bag, showing a clasp embodying the principles of my invention, with clasp in clasping position;

Figure 2 is an edge view of the bag, showing the clasp in clasping position;

Figure 3 is a sectional detail of the bag and 50 frame, showing in full lines, the clasp in fastening or clasping position, and, in dot-and-dash lines, the clasp in released position; and

Figure 4 is an enlarged sectional detail, 55 showing the fastener and method of attaching it to the bag frame.

Referring with greater particularity to

the drawings, in which an embodiment of any invention has been shown, 1, in a general way, represents a lady's hand-bag, of leather or other suitable material, having 60 hinged metallic frame-members 2 and 3 hingedly secured at the point 4, and provided with the ordinary carrying strap 5.

In the construction shown, the frames 2 and 3 are of the ordinary channelled metallic character, having a leather, or other suitable covering secured tightly thereabout, with the edges of the covering secured to the inner faces of the frames, and the ends of the purse, or bag, body 1 secured in like manner within the channel members.

A leather tab 6 is positioned upon the front side of the body of the bag and is secured at its upper edge to the inside of the frame 3, from which it hangs freely against the bag 75 body, as shown in Figures 1 and 3.

My improved clasp comprises a member 7 constituted of a U-shaped metallic stamping having a vertically disposed section 8 adapted, when in clasping position, to lie 80 flush against the rear face of the channelled member 2 and bearing a hinge member 9 formed at its lower edge, to which is hingedly secured an attaching plate 10 adapted to be riveted or otherwise secured 85 against the inner face of the member 2. The horizontal top section 11 of the stamping is integrally formed with the vertically disposed frontal section 12, the section 11 being of sufficient width to permit the sections 90

8 and 12 to normally loosely embrace the members 2 and 3 to cause them to be retained in close relation. The section 12 is provided with a circular pendant 13 having 95 formed about its edges tines 14 adapted to 90 embrace, in mounted position, an ornamental disc of any desired design and character. The outer face of the channelled member 3 is provided with a small button or nodule 16 formed by either heading down a brass rivet or forming a slight bulge in the frame member, itself, the purpose of the nodule being to frictionally engage the under face 100 of the section 12 of the member 7, when this member is brought into clamping position, 105 thus aiding in bringing the frames 2 and 3 into tighter and closer relation with each other, while, at the same time, protecting the leather from abrasion and wear, through preventing the clasp coming directly into 110 frictional contact with it.

Once the clasp is secured in clasping po-

sition about the hand-bag frames, these members are brought into and retained in close relationship and all possibility of accidental opening removed, this closed relationship being maintained even when the bag is dropped or otherwise subjected to rough usage.

In opening the bag, the lower end of the tab 6 is grasped and raised to the position shown by the dotted outline shown in Figure 3, this upward swinging movement of the tab carrying and raising the disc 15 with it and serving to swing the member 7 upon its hinge 9 and release the channelled member 3 from its grasp.

Having thus described my invention, I claim, and desire to secure by Letters Patent of the United States:

1. In a device of the class described, the combination with a hand-bag having hinged frame members, of frictional engaging means borne by one of said frame members, a resilient metallic clasp member consisting of a U-shaped stamping having one section thereof adapted for hinged attachment to the lower edge of the frame member opposite the member to be clasped and adaptable for swinging movement in a plane at right angles to that of said frame members, the free section of said clasp being adapted to

engage said frictional engaging means carried by the frame member opposite that to which said clasp is hinged, and a flexible tab attached by its upper edge secured to that frame member intended for clasping by said clasp and adapted for releasing said U-shaped stamping from its clamping position.

2. In a device of the character described, the combination with a hand-bag having hinged frame members, of frictional engaging means borne by one of said frame members, a resilient metallic clasp member consisting of a U-shaped stamping having one section thereof adapted for hinged attachment to the lower edge of that frame member opposite that frame member intended to be clasped and adaptable for swinging movement in a plane at right angles to that of said frame members, the free section of said clasp being adapted to engage said frictional engaging means borne by the frame member opposite that frame to which said clamp is hinged, and a flexible tab attached by its upper edge to that frame member carrying the frictional engaging means and adapted for releasing said clasp from its clamping position.

In testimony whereof I have affixed my signature.

DEZSO BALAZS.
